UNITED STATES PATENT OFFICE.

HARVEY ABRAMS AND HICKS C. ABRAMS, OF LONG PINE, NEBRASKA.

CURTAIN AND SHADE HANGER.

1,221,264.

Specification of Letters Patent.

Patented Apr. 3, 1917.

Application filed October 4, 1915. Serial No. 54,025.

To all whom it may concern:

Be it known that we, HARVEY ABRAMS and HICKS C. ABRAMS, citizens of the United States, residing at Long Pine, in the county of Brown and State of Nebraska, have invented certain new and useful Improvements in Curtain and Shade Hangers, of which the following is a specification.

This invention contemplates an improved shade and curtain holder and has as its primary object to provide a device of this character which may be readily attached to or detached from a window without marring the woodwork thereof and which will eliminate the necessity of using nails or other fastening devices for holding it in position.

The invention has as a further object to provide a device of this character which may be adjusted to fit windows of various widths and which when in place, will present a neat and attractive appearance.

And a still further object of the invention is to provide an adjustable mounting for the shade brackets employed of such character that the said brackets may be easily positioned to receive shade rollers of different lengths.

Other and incidental objects will appear as the invention proceeds and in the drawings wherein we have illustrated the preferred embodiment of the invention and wherein similar reference characters designate corresponding parts throughout the several views.

Figure 1 is a perspective view showing our improved device applied to a conventional type of window,

Fig. 2 is a sectional view more particularly showing the mounting of the shade brackets employed,

Fig. 3 is a fragmentary front elevation showing the yieldable locking member carried by one of the curtain rod supporting arms and adapted to engage the free end of said rod for holding the rod in fixed position, and

Fig. 4 is a side elevation of the outer terminal of the said curtain rod supporting arm particularly illustrating the manner in which the free end of the said arm is bent to provide the locking member for the free end of the curtain supporting rod.

In carrying out our invention, the body portion of the device is formed to include a pair of attaching members 10 which are offset adjacent the inner extremities thereof,

as particularly shown in Fig. 2 and are terminally screw threaded to receive a connecting sleeve 11, the sleeve 11, of course, being provided with right and left hand screw threads. The outer extremities of the attaching members are flattened and are provided with laterally directed terminal lugs or arms 12.

In Fig. 1 of the drawings, we have shown our improved device in connection with a conventional type of window 13. The attaching members are arranged adjacent the upper end of the window to extend transversely thereof with the lugs 12 engaging opposite longitudinal edges of the window casing, and with the flattened portions of the said members seating against the front face of the casing. When so positioned, the connecting sleeve 11 will be supported in spaced relation to the adjacent face of the casing so that it may be readily turned for drawing the lugs into engagement with the casing and thus fixing the device in position upon the window. In this connection, it is to be noted that we thus provide a construction wherein the use of nails or other fastening devices is eliminated and which may be readily attached to or detached from without marring the woodwork of the window. Furthermore, by means of the sleeve 11, the attaching members may be adjusted to fit windows of various widths.

Mounted upon the outer flattened extremities of the attaching members are shade brackets 14, the outer extremities of which are arranged to project laterally from the said attaching members and are formed with openings to respectively receive the trunnions at opposite ends of a shade roller 15, the roller being conventionally illustrated. The shade brackets are each substantially L shaped and the inner extremities thereof are arranged to seat flatly against the flattened portions of the attaching members 10 and are longitudinally slotted to freely receive bolts or other suitable fastening devices 16 fitted through the attaching members. Associated with the shade brackets are stop lugs or pins 17 arranged to project laterally from the attaching members to engage over the upper edges of the slotted terminals of the brackets adjacent the inner ends thereof as more particularly shown in Fig. 2.

It will now be noted that by releasing the nuts of the bolts 16, the shade brackets may

be adjusted longitudinally of the attaching members to receive shade rollers of different lengths while the stops 17 will serve as guides for the said brackets and overcome 5 any tendency of the brackets to pivot upon the bolts.

Projecting laterally from the outer extremities of the attaching members are curtain rod supporting arms 18 and 19 respectively which extend outwardly beyond the shade brackets 14 and are located substantially in the same plane therewith. These arms are each preferably formed from a single length of resilient wire or other suitable material. The arm 18, at its outer extremity, is bent laterally to provide a depending terminal to which is pivotally connected a curtain supporting rod 20. The arm 19 is also bent at its outer extremity, to 20 define a depending loop or locking member 21 adapted to yieldably engage the free end of the curtain supporting rod for supporting the rod in substantially horizontal position to receive a curtain. It will be noted that the outer extremity of the rod 19 is bent laterally and in a downward direction to form one jaw of the locking member and is then rebent upon itself upwardly to form the other jaw, the said last mentioned jaw being deflected or offset laterally out of the plane of the said first mentioned jaw. In this manner, the jaws may be so positioned relative to each other that normally, the inner faces thereof will nearly 35 touch a common plane so that when the free extremity of the rod 20 is inserted between the jaws, the said jaws will yieldably grip the rod for effectually holding it in a fixed position, while, at the same time, the free 40 end of the rod may be easily inserted between the jaws owing to the fact that the upper extremities thereof are out of register. However, to facilitate the operation of engaging the rod between the jaws, the upper 45 extremity of the outermost jaw is provided

with a laterally directed terminal curving away from the upper extremity of the innermost jaw and by first engaging the free end of the rod with the said terminal, downward force may then be applied to the rod 50 to urge the free extremity thereof between the jaws.

It will therefore be seen that we provide a very simple and efficient construction and it will be noted that the curtain supporting 55 rod 20 is of such length as to allow for the longitudinal adjustment of the attaching members. Any conventional type of curtain may be connected to this rod in any suitable manner to depend in front of the shade 60 so that the entire device in practice, will present a neat and attractive appearance.

Having thus described our invention, what we claim and desire to secure by Letters Patent is:

65

1. A device of the character described including a body portion, fixed arms extending therefrom with one of said arms provided with relatively straight downwardly converging gripping jaws, and a horizontally arranged curtain supporting rod pivotally connected at one extremity to the other of said arms to move in a plane at substantially right angles to the said arms with the rod movable to a position with the free 75 end thereof wedged between said jaws.

2. A device of the character described including a body portion, arms fixed to the body portion to extend outwardly therefrom, one of said arms being provided with a hook having inwardly converging jaws, and a curtain supporting rod pivotally connected to the other of said arms with the rod movable to a position with the free end thereof wedged between the jaws of said 85 hook.

In testimony whereof, we affix our signatures.

HARVEY ABRAMS. [L.S.]
HICKS C. ABRAMS. [L.S.]
